UNITED STATES PATENT OFFICE.

WILLIAM C. IRWIN, OF ROCHESTER, NEW YORK, ASSIGNOR OF ONE-HALF TO FRANK J. HUNT, OF ROCHESTER, NEW YORK.

COMBINATION PUZZLE AND GAME.

Application filed July 31, 1923. Serial No. 654,946.

To all whom it may concern:

Be it known that I, WILLIAM C. IRWIN, a citizen of the United States, residing at Rochester, in the county of Monroe and State 5 of New York, have invented certain new and useful Improvements in Combination Puzzles and Games, of which the following is a specification.

The object of this invention is to provide 10 a combination puzzle and game comprising a series of blocks or plates having an irregular outline which blocks must first be arranged into the layout of picture or plan and then rearranged into the layout of another picture or plan representing the game.

These and other objects of this invention will be fully illustrated in the drawing, described in the specification and pointed out in the claims at the end thereof.

20 In the accompanying drawing:

Figure 1 is a perspective view of the combination puzzle and game in the form of the plan of a landscape which is adapted to be transformed into a golf course.

25 Figure 2 is a perspective view of the combination puzzle and game illustrated in Figure 1 after it has been transformed into a golf course.

Figure 3 is a detail perspective view of 30 one of the blocks which make up the plan of the landscape in the one form and the golf course in the other form.

In the several figures of the drawing like reference numerals indicate like parts.

35 The combination game and puzzle forming the subject matter of my present invention is similar to the puzzles or games in which a picture is to be formed by a series of blocks by placing them against one another. However 40 my invention goes further than this, in that after one picture is formed by the blocks, the blocks must be rearranged to form another slightly different picture or plan that can be used for the purpose of playing another kind of game by the person 45 or persons assembling the plan or chart of the first game.

The form of the puzzle and game in which my invention is illustrated in the drawing 50 is that of a landscape that can be transformed into a four hole golf course. It comprises a series of blocks 1 having irregular outlines that can be assembled into the picture of the landscape illustrated in Figure 55 1. For this purpose some of the blocks

are provided with a raised ridge 2 which when assembled as illustrated in Figure 1 form four diagonal raised lines leading from a raised circle formed in the center of the landscape.

60 Among the many irregular blocks 1 are a few that are similar to each other and it is the object of this game to locate these blocks and rearrange them by interchanging their position. Thus the blocks marked 5 may be interchanged with the block marked 5^A the block marked 6 interchanged with the block marked 6^A and so on until the plan of the landscape illustrated in Figure 1 has been transformed into the plan of

70 75 the golf course illustrated in Figure 2. When the blocks are interchanged in this manner some of the blocks having the raised ridge formed on it are replaced by blocks without the ridges so that while a breach is formed in three of the diagonal ridges of the landscape a "hazard" in the form of a short ridge is formed in front of each of the four "holes" of the golf course. The 80 openings in the diagonal ridges of the landscape together with the opening of the central circle in this way provide a continuous course over which a golf ball 7 may be rolled and successively played into each of the "holes" with the "hazards" formed 85 by the shifted ridge sections obstructing the direct passage from one hole to the other.

I claim:

1. In a combination puzzle and game, 90 the combination of a single series of blocks having irregular outlines adapted to interlock with one another and having portions of a picture, plan or chart illustrated at the top thereof, a number of said blocks 95 being duplicates of each other in outline but having dissimilar portions of the picture, plan or chart provided thereon, said duplicate blocks with their dissimilar portions of the picture, plan or chart being adapted to be interchanged to form another picture, plan or chart having the same combined outline but illustrating a different picture, plan or chart with the same single 100 series of blocks and the same portions of the picture, plan or chart provided thereon.

2. In a combination puzzle and game, the combination of a single series of blocks having irregular outlines adapted to interlock with one another and having a portion 110

of a picture, plan or chart provided at the top thereof, said blocks being adapted to be interchanged to form one predetermined picture, plan, or chart into another picture, plan or chart having the same combined outline with the same single series of blocks and the same portions of the picture, plan or chart provided thereon.

3. In a combination puzzle and game, the combination of a single series of blocks having irregular outlines adapted to interlock with one another and having portions of a picture, plan, or chart provided at the top thereof, a predetermined picture, plan or

chart adapted to be formed by the portions of pictures, plans or chart carried by said blocks, a number of said blocks with its portion of the picture, plan or chart being adapted to be interchangable with each other to form from said first predetermined picture, plan or chart a second predetermined picture, plan or chart having the same combined outline with the same single series of blocks and the same portions of the picture, plan or chart provided thereon.

In testimony whereof I affix my signature.

WILLIAM C. IRWIN
